UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SNAP-SWITCH.

1,251,771.

Specification of Letters Patent.

Patented Jan. 1, 1918.

Application filed October 12, 1916. Serial No. 125,134.

To all whom it may concern:

Be it known that I, MONROE GUETT, a citizen of the United States, residing at Hartford, in the county of Hartford and State 5 of Connecticut, have invented certain new and useful Improvements in Electric Snap-Switches, of which the following is a specification.

This invention relates to electric snap 10 switches. In Letters Patent No. 1,163,084 issued to me December 7, 1915 is disclosed a switch of the present type. The primary purpose of the present invention is to provide means of an effective nature by which 15 I can secure all the advantages accomplished by the switch set forth in said Letters Patent but by different means.

In the drawings accompanying and forming part of the present specification I have 20 shown in detail one of the several convenient forms of embodiment of the invention which will be set forth fully in the following description. I do not restrict myself to this particular disclosure; I may depart 25 therefrom in several respects within the scope of the invention defined by the claims following said description.

Referring to said drawings:

Figure 1 is a top plan view of a switch 30 involving the invention.

Fig. 2 is a section on the line 2—2, looking in the direction of the arrow, the switching member being on.

Fig. 3 is a similar view with the switching 35 member off.

Fig. 4 is a horizontal section on the line 4—5 of Fig. 2, looking upward and showing certain of the parts in different positions by dotted and full lines.

Fig. 5 is a section on said line 4—5, looking downward.

Fig. 6 is a similar view showing the detents in their inoperative positions by full lines and in operative positions by dotted 45 lines.

Figs. 7 and 8 are sections through the spindle and spring taken just above the spring, the first of these views showing the spring means as tensioned, while the other 50 illustrates the spring means in the initial position thereof.

Fig. 9 is a sectional detail, the section being on the line 9—9 of Fig. 4, looking in the direction of the arrow.

Like characters refer to like parts

throughout the several views which are on different scales.

My switch involves in its make-up a switching member of suitable type mounted for back and forth movement about an axis; that is to say the switching member may be 60 rotatively moved step by step in either direction, or it may be merely oscillatory. In the present case the action is a rotary one.

The different parts of the switch may be 65 sustained in any desirable way; for instance they may be carried upon a base as 2 generally of porcelain. The switching member may be of any suitable nature. As shown it consists of a commutator denoted in a 70 general way by 3, having two poles as 4 insulated as is customary from each other and co-operative with contacts as 5 shown as being of clip type mounted upon the insulating base or body 2. This commutator 75 and contacts may be arranged exactly as shown in the prior Letters Patent.

Fastened by screws or otherwise to the body or base 2 is a suitable detent member, the ratchet plate 6 answering satisfactorily 80 in this particular. As represented this detent or ratchet member 6 is fastened to the bottom of the cavity 8 in the upper side of the body 2 approximately centrally thereof. Extending through and turning in a practically central opening in the detent member 6 is a spindle as 9. Interposed between the spindle and the detent plate is a bushing 9', the spindle being held against accidental withdrawal in some suitable way as by the 85 washer 10 connected therewith as common. The spindle 9 extends freely through the switching member. It may be turned in any suitable way as by the handle 12 connected rigidly therewith as by the screw 13 as familiar. Encircling the spindle 9 is the coiled spring 14, the opposite ends of which are outturned as at 15 and 16, the elements 17 and 18 being disposed between these outturned ends as shown best in Fig. 8 which 95 illustrates the normal relation or when the parts are at rest. The element 17 rotates with the spindle 9, while the part 18 turns with the switching member 3, all as common in snap movements. As a matter of fact the 100 construction hereinbefore described is generally speaking like that shown in my prior Letters Patent which is merely one structure as may be inferred, in connection with which the invention is advantageously used.

110

ble. As the spindle 9 is turned for instance in the direction of the arrow in Fig. 7, the part 17 engaging the off-set portion 15 of the spring, the switching member being held 5 against action during this time, the spring will be tensioned, and when the requisite tension is reached, the switching member will be released so that the tensioned spring through the medium of the off-set 16 thereof 10 acting against the part 18 can impart a snap movement to the switching member to move the same either to the on or to the off position. Should the spindle be turned in the direction opposite the arrow, the part 17 by 15 engaging the off-set 16 will tension the spring, and when the necessary tension is obtained, the off-set 15 by acting against the part 18 can snap the switching member to the on or the off position as the case may be. 20 The fixed detent 6 as shown is in the form of a disk, having a suitable number of peripheral teeth as 19, 20, 21 and 22. Four of these teeth are shown, and they are equidistantly disposed. Any other suitable 25 detent might be provided. In conjunction with the detent or ratchet plate 6 are stop elements as 23, 24, 25 and 26, these stop elements being slidably carried in the present case by the switching member. Although 30 there are four of such stop elements, this may not in all cases be necessary. In the present case said stop elements are slidably supported by the switching member, the base plate 27 constituting a part of the switching 35 member, being a suitable carrier for them. These stop elements slide in radial grooves as 28 formed in the lower side of the said base plate, and in the annular depending flange 29 thereof. The front ends of the 40 grooves 28 are open and normally the inner ends of the stop elements abut against the back or closed ends of said grooves or slots as shown best in Fig. 9. The said stop elements 23, 24, 25 and 26 are held suitably in their 45 retracted positions, the coiled spring 30 answering satisfactorily in this connection. The spring is of annular form and is coiled, the ends being hooked together as at 31 (Fig. 4), the spring encircling the four stop elements and being seated in notches as 32 50 formed in the outer faces thereof, by reason of which one spring serves for all of the stop elements. Said stop elements have shouldered or off-set portions 33 which normally 55 engage adjacent faces of the teeth 19, 20, 21 and 22 of the detent or ratchet plate 6 as shown in Fig. 5. To effect the movement of the stop elements to releasing position any suitable means may be provided, the double 60 lobed cam 34 being shown for this purpose, said cam being keyed or otherwise suitably connected with the spindle 9 for rotation therewith.

The parts are shown as occupying their 65 neutral or at rest positions by full lines in

Fig. 4. Fig. 5 also illustrates the stop elements 23, 24, 25 and 26 when the switching member is either on or off. The stop elements 25 and 26 engage adjacent faces of the teeth 21 and 22, while the stop elements 23 and 24 engage adjacent faces of the teeth 19 and 20 in said Fig. 5. It will be assumed that it is desired to shift the switching member. In this event the following procedure will be adopted: Through the manipulation 70 of the handle 12, the spindle 9 will be turned, for instance in the direction of the curved arrows in Figs. 4, 6 and 7. Owing to the fact that the stop elements 23, 24, 25 and 26 abut against the teeth 19, 20, 21 and 22 of the fixed ratchet plate 6, it is obvious that on the initial turning movement of the spindle, the switching member 3 will not be operated. The spring 14, however, will be tensioned through the turning of the spindle 85 in the manner already described and as said spindle turns, the cam 34 will rotate therewith and engaging the butts of the four stop elements will move said stop elements outwardly as shown by dotted lines in Fig. 4. 90 As the stop elements 23, 24, 25 and 26 are moved radially outward by the turning cam 34, the spring 14 during this time being tensioned, the off-set portions 33 of the several 95 stop elements will be moved free of the several teeth 19, 20, 21 and 22, being carried free of said teeth just about the time the spring 14 is under maximum compression. When the shouldered portions 33 of the several stop elements are free of the respective 100 restraining teeth 19, 20, 21 and 22, the switching member 3 will be released, so that the tensioned spring 14 can snap the switching member to the on or the off position as 105 the case may be. As the several stop elements 23, 24, 25 and 26 are slid outward, they expand the annular spring 30 so that the spring 30 on its contraction can at the proper time restore the several stop elements 110 instantaneously to their active positions. That is to say after the switching member commences its movement, the several stop elements are slid at an accelerated speed inwardly, so that their shouldered portions 33 115 can engage the teeth of the detent or ratchet plate 6 and thus arrest further motion of the switching member when the same is in the correct position which may be either on or off. It will be understood that the action of the stop elements in point of time is practically the same as that described in connection with the swinging stop elements of my Letters Patent, although said Letters Patent, as will be apparent, contemplated in its 120 scope the use of movable stop elements of 125 any suitable type. The present case is confined to stop elements which slide, as to one of the features thereof.

It will be understood from the observations already made that two stop elements 130

control the motion of the switching member in one direction and that the other two control the motion of the switching member in the opposite direction. For instance should it be desired to move the switching member in the direction of the arrow in Fig. 7, the stop members 23 and 26 will be simultaneously moved outward clear of the adjacent teeth 19 and 22, but the switching member cannot be turned until the stop members 24 and 26 are disengaged from the teeth 20 and 21 respectively, these two stop elements 24 and 25 jointly controlling the movement of the switching member in the direction indicated. Should it be desired to turn the switching member to the right opposite the arrow in Fig. 7, the stop members 24 and 25 are simultaneously moved free of the teeth 20 and 21, but the switching member cannot move in this particular direction until the stop members 23 and 26 are moved to releasing position.

What I claim is:

1. A switch comprising a switching member, a detent, a plurality of stop elements slidably supported by the switching member, an annular spring surrounding and acting against the stop elements to hold the same normally in engagement with said detent, spring means to apply its effect to the switching member, and means for moving the stop elements to switch member releasing position and at the same time tensioning said spring means, said tensioned spring means when the stop elements free the switching member shifting the latter.
2. A switch comprising a switching member, a detent, a plurality of stop elements slidably supported by the switching member, an annular coiled spring surrounding the stop elements and normally holding the same in engagement with the detent, spring means to apply its effect to the switching member, and means for moving the stop elements to switch member releasing position and at the same time tensioning said spring means, said tensioned spring means when the stop elements are freed, shifting the switching member.

the stop elements free the switching member, shifting the latter.

3. A switch comprising a stationary detent, an oppositely rotative switching member, stop elements supported by the switching member for radial sliding movement, an annular coiled spring surrounding the stop elements and normally holding the same in engagement with said detent, a spindle extending freely through the switching member, a spring interposed between the spindle and the switching member, and a cam rotative with the spindle for moving the stop elements free of the detent on opposite movements of the spindle.

4. A switch comprising a switching member, a detent, a plurality of stop elements movably supported by the switching member, an annular spring surrounding the stop elements and normally holding the same in engagement with the detent, spring means to apply its effect to the switching member, and means for moving the stop elements to switch member releasing position and at the same time tensioning said spring means, said tensioned spring means when the stop elements free the switching member, shifting the switching member.

5. A switch comprising a switching member, a detent, a plurality of stop elements movably supported by the switching member, an annular coiled spring surrounding the switching elements and normally holding the same in engagement with the detent, spring means to apply its effect to the switching member, and means for moving the stop elements to switch member releasing position and at the same time tensioning said spring means, said tensioned spring means when the stop elements are freed, shifting the switching member.

In testimony whereof I affix my signature in the presence of two witnesses.

MONROE GUETT.
